UNITED STATES PATENT OFFICE.

JOHN WILEY EDMANDS, OF NEWTON CENTER, MASSACHUSETTS, ASSIGNOR TO CENTRAL RAILWAY SIGNAL COMPANY, OF PITTSBURGH, PENNSYLVANIA, A CORPORATION OF NEW JERSEY.

RAILWAY SIGNAL-FUSEE.

1,236,692.

Specification of Letters Patent.

Patented Aug. 14, 1917.

Application filed October 24, 1916. Serial No. 127,474.

To all whom it may concern:

Be it known that I, JOHN WILEY EDMANDS, a citizen of the United States, residing at Newton Center, in the county of 5 Middlesex and State of Massachusetts, have invented certain new and useful Improvements in Railway Signal-Fusees, of which the following is a specification, reference being had therein to the accompanying 10 drawing.

This invention relates to improvements in railway signal fusees, and pertains to a novel manner of attaching a spike-carrying plug to the end of the fusee.

15 It is well known to those skilled in this art that railway signal fusees have a spike applied to one end and that this spike is attached to the fusee through the medium of a plug.

20 The object of this improvement is to prevent the spike-holding plug from loosening in the end of the fusee tube and become detached, and also to form a more perfect closure and seal at the spike end of the 25 fusee, in order to prevent moisture from entering the tube and being absorbed by the burning composition, thereby injuring the burning quality of the said composition.

The specifications of railroads require 30 that the spike-end closure must withstand a direct pull of seventy-five pounds, and the usual method of gluing or cementing the plugs within the tubes, unless very carefully and thoroughly done would not stand 35 the required test, and also are apt to become loosened and fall out, owing to dampness and constant handling by railway employees before being used.

Figure 1 is a perspective view of a fusee, 40 showing the spike-carrying end in section.

Fig. 2 is a longitudinal sectional view of the spike-end of a fusee provided with my improvement.

The construction of railway signal fuses 45 is so well known to those skilled in the art that it need only to be described and shown briefly to enable my improvement to be understood. The fusee tube 1 is constructed in the usual manner of paper and contains the 50 burning compound 2.

My improved spike-carrying plug comprises an inner portion 3 and an outer portion 4. The outer end of the inner plug 3 is provided with a recess 5 forming an an-

5 nular projecting flange 6, and the outer

6 member or plug 4 is provided with a central projection 7, forming an annular shoulder 8. As shown, the spike 9 passes through the 63 inner and outer plug members or portions 3 and 4 and preferably is provided with a large flat head 10. Also preferably the inner portion of the spike is roughened, as shown at 11, and this roughened portion 65 may extend into the plug portion 4, as shown by means of which the spike is more permanently connected with the plug portions.

In assembling the parts the spike 9 is driven through the inner plug portion 3 before it is placed within the fusee tube 1. Preferably the plug portion 3 is cemented 70 to the inner wall of the tube 1, as shown at 12, and the end 13 of the paper tube 1 is doubled inward, as shown, and extends into the recess 5, formed in the outer end of the 75 inner plug member 3. When the inner plug portion 3 is in position in the fusee, then the outer plug portion 4 is passed over the spike and its projection 7, tightly enters the inwardly turned portion 13 of the tube 80 and it also is preferably cemented in position.

By this construction, it will be observed that the inturned end of the tube locks the inner plug member 3 within the tube, and 85 that the outer plug portion 4 locks the turned end of the tube so that the spike-carrying plug cannot be accidentally removed from the tube without tearing away the end of the tube. In this manner the plug-carrying portions and the fusee tube are locked 90 together and a very firm, permanent and efficient spike-carrying plug construction is provided.

Furthermore, this manner of carrying the 95 spike plug within the end of the fusee tube makes a water and moisture-proof closure to prevent the entrance of moisture within the tube to deteriorate and affect the chemical compound therein, and prevents absolutely 100 the loosening up of the plug and its accidental removal or falling out.

In practice, these railway fusees are sometimes carried a long time by the railway employee before it is used, and is subjected to 105 considerable handling and oftentimes to rain and, of course, is always subjected to the change of climatic conditions.

It is also well-known to those skilled in this art that the railway signal fusees are con- 110

2
 sucted to burn for a predetermined period of time and have become known as five minute, ten minute, etc., fusees. It is also well-known to those skilled in this art that the time burning of the chemical composition is materially affected by moisture. That is to say, the time of burning is lengthened by the dampening of the chemical compound. The fusee is made to burn a specified length of time and the railroad operators depend upon and are controlled in the movement of the trains according to the predetermined period of burning. It is, therefore, necessary to prevent changed conditions in the chemical composition, such as is occasioned by the entrance of moisture, and, as before stated, the railroads subject the plug to a pulling contest, all of which conditions must be met to make the article acceptable to the railroads. This improvement meets these conditions fully in the manner above stated.

Having thus described my invention, what I claim and desire to secure by Letters Patent is:

1. The combination with a fusee tube, of a spike-carrying plug comprising inner and

outer plug portions interlocking with the end of the fusee tube, and a spike passing through the two plug portions and projecting beyond the outer plug portion. 30

2. The combination with a railway signal fusee, of a spike-carrying plug comprising inner and outer plug portions, one portion having a recess and the other a projection, and the end of the fusee doubled into the recess and around the projection. 35

3. The combination with a railway signal fusee, of a spike-carrying plug comprising inner and outer plug portions, the inner portion having a recess in its outer end forming a surrounding flange, the end of the fusee tube doubled into the said recess, the outer plug portion having a central projection extending into the said recess and 45 tightly fitting the inturned end of the tube, and a spike passing through the two plug portions.

In testimony whereof I hereunto affix my signature in the presence of two witnesses. 50

JOHN WILEY EDMANDS.
